UNITED STATES PATENT OFFICE.

JOHN AUGUSTUS HICKS, OF SUMMIT, NEW JERSEY; ARTHUR W. HICKS ADMINISTRATOR OF SAID JOHN AUGUSTUS HICKS, DECEASED.

SEALING-CAP FOR VESSELS.

1,082,696.

Specification of Letters Patent.

Patented Dec. 30, 1913.

Application filed April 1, 1910. Serial No. 552,896.

To all whom it may concern:

Be it known that I, JOHN AUGUSTUS HICKS, a citizen of the United States, residing at Summit, Union county, New Jersey, have invented certain new and useful Improvements in Sealing-Caps for Vessels, of which the following is a specification.

My invention relates to sealing caps for vessels.

- 10 The object of my invention is to provide a sealing cap with a compressible material, having the face which comes in contact with the vessel and its contents, pliable, non-absorbent and adhesive.
- 15 In order that those familiar with the art may understand and make use of my invention, I will describe it as follows, in connection with the accompanying drawings, in which:
- 20 Figure 1 illustrates a sealing wafer made according to my invention. Fig. 2 illustrates the same in position in a metal cap. Fig. 3 illustrates the thin layer of material which forms the adhesive portion of the wafer. Fig. 3^a is a top view of Fig. 3. Fig. 4 illustrates the sealing wafer as held compressed on the vessel. Fig. 5 illustrates the metal cap removed from the sealing wafer and vessel, the wafer as a whole adhering 30 to the vessel. Fig. 6 illustrates a part only of the wafer adhering to the vessel, such part being the adhesive face or underlining. Fig. 7 illustrates the cap with the compressible material of the wafer removed from the 35 vessel.

In the drawing, A denotes the compressible portion of the lining of the cap, B denotes the thin or wafer-like adhesive underlining, C denotes the metal cap, and D denotes the neck and top of a bottle.

I employ a compressible material A, and face it with a thin, pliable, non-absorbent, adhesive material, B. I assemble these materials together and place them in the cup 45 of a sealing cap with the adhesive, non-absorbent and pliable face so arranged that when the cap is applied to a vessel by pressure, the said adhesive face will be in contact with the vessel surface and its contents, 50 and will adhere to the vessel's surface and produce a hermetical seal. When the cap is removed from the vessel to empty the contents, which are usually of a gaseous na-

ture, the wafer will stick to the vessel sufficiently long to cause the gases from the vessel to discharge with a pop. 55

When the sealing cap is to be used on vessels filled with malt liquor which is to be sterilized under heat, I back up the compressible material of my wafer with a stiff 60 material which is sufficiently adhesive under heat to cement itself to the compressible material, and thereby form a composite wafer of sufficient stiffness and adhesiveness to stick on the vessel, while the metal cap is 65 being removed, and to be blown from the vessel by the internal gaseous pressure with a loud pop.

I usually employ as my adhesive material an antiseptic substance. 70

Having now fully described my invention and the manner in which I have embodied it, what I claim as new and as my invention and desire to secure by Letters Patent is—

1. A bottle closure comprising a metal cap 75 adapted to be secured over the mouth of the bottle, and a lining in the cap having an impervious adhesive face adapted to adhere hermetically to the bottle mouth, the lining being unattached to the cap, whereby 80 in removing the cap from the bottle the cap will separate from the lining, leaving the latter adhering to the bottle mouth so as to be blown immediately therefrom with an explosive sound by the pressure of gas in 85 the bottle.

2. A bottle closure comprising a cap adapted to be secured over the mouth of the bottle, a yielding pad in the cap, and a facing therefor consisting of an impervious adhesive wafer, the pad and wafer constituting a lining unattached to the cap but adapted to adhere hermetically to the bottle mouth, whereby in removing the cap from the bottle the cap will separate from the lining, leaving the latter adhering to the bottle mouth so as to be blown immediately 95 therefrom with an explosive sound by the pressure of gas in the bottle.

In testimony whereof, I have signed my 100 name to this specification in the presence of two subscribing witnesses.

JOHN AUGUSTUS HICKS.
